UNITED STATES PATENT OFFICE.

WILLIAM HENRY HAZLITT, OF TORONTO, ONTARIO, CANADA.

SANITARY CUSPIDOR.

Application filed July 28, 1927. Serial No. 208,997.

My present invention pertains to sanitary 5 cupidors; and has for its general object the provision of a sanitary cuspidor which while simple and inexpensive in construction is highly efficient in the elimination of expectorations and the like and is therefore always in a wholesome state.

To the attainment of the foregoing, the invention consists in the improvement as 10 hereinafter described and definitely claimed.

In the accompanying drawings forming part of this specification:

Figure 1 is a diametrical vertical section of my novel cuspidor, the same being 15 shown in proper relation to a floor.

Figure 2 is a top plan view of the cuspidor per se.

Figure 3 is a detail vertical section hereinafter explicitly referred to.

Similar numerals of reference designate 20 corresponding parts in all views of the drawings.

I show in Figure 1 a floor 1 which may be the floor of any apartment or any other 25 place where it is desired to locate my novel cuspidor, and I also show in Figures 1 and 2 the cuspidor per se.

Among other elements my novel cuspidor 30 comprises an upright pipe 1^x designed to be connected with a source of water supply and to maintain the head of water necessary for the maintenance of the cuspidor in a thoroughly sanitary and wholesome state. The said pipe 1^x is provided at an intermediate 35 point of its length with a lateral arm 2 which at its inner end is merged into a vertically disposed terminal 3.

The bowl of my novel cuspidor is cast 40 or molded or otherwise appropriately formed on the pipe, relatively arranged as shown; and it will be understood within the purview of my invention, the bowl may be made of porcelain with vitrified surfaces or of cast iron appropriately enameled or of any 45 other material compatible with the purpose of the cuspidor.

The bowl includes among other elements 50 or features a concavo-convex bottom 4, the essentially concave side of the said bottom 4 being provided with an upstanding rounded protuberance 5. This latter is provided with a central vertically disposed bore 6 in which is arranged the upstanding terminal 3 of the pipe and so that the surface of the 55 protuberance 5 is flush with the upper end of

the terminal 3. The bowl also includes an upper rim portion 7 shouldered at 8 to bear on and be supported by the floor 1. In the said rim 7 is an annular bore 8^x, the said bore 8^x being designed to receive water from the upper end of the upright pipe 1^x, Figure 3, and being in communication with inwardly and downwardly directed apertures 9 spaced apart and adapted to jet water against the concave bottom 4 and about the 60 protuberance 5. The body of the cuspidor also includes overflow openings 10 which are in communication with passages 11 disposed under the bottom 4 and arranged to discharge into a pendent waste conduit 12, the latter 65 being designed to be connected with a trap, not shown, in connection with a conventional or other suitable sewer pipe, also not shown.

With a view to averting breakage when the bowl or body is formed of porcelain, a shoulder 13, Figure 1, is provided adjacent to the apertures 9 and between said apertures 9 and the inner surface of the rim 7.

Arranged in the bowl or body and about the base of the protuberance 5 is a circular 80 series of discharge apertures 14. The said apertures 14 are vertically disposed in close proximity to the base of the said protuberance 5 and lead directly from the upper side of the bottom 4 to the waste conduit 12. 85 Manifestly under ordinary working conditions, the water jetted on the bottom 4 from the apertures 9 will pass together with expectorations through the apertures 14 and to the waste conduit 12, and hence there will be 90 no liability of filth collecting in the cuspidor bowl and about the protuberance 5. In the event however that the apertures 14 are inadequate for any reason to carry off the water and expectorations, any overflow will 95 be taken care of by the overflow apertures 10 and the conduits 11 in communication therewith.

It will be apparent from the foregoing 100 that my novel cuspidor is provided throughout with a smooth surface on which impurities cannot lodge, and consequently the surface can be easily kept perfectly clean. Again it will be appreciated that the entire 105 surface of the cuspidor is constantly flushed with clean water incident to the use of the cuspidor and this contributes materially to the sanitary character of the cuspidor. It will further be apparent that the cuspidor offers but slight projection above the floor 1 110

and therefore there is little liability of any one stumbling over the cuspidor or disturbing the contents thereof.

While the cuspidor is preferably employed 5 in the relation shown and described to a floor such as 1, I would have it understood that within the purview of my invention the cuspidor may be appropriately supported at the sides of beds in hospitals or hotels, at the 10 side of dental chairs and in various other relations.

When my novel cuspidor is formed of porcelain it may be reinforced at the points deemed necessary to reinforce, but the reinforcement *per se* is not of my invention and I therefore deemed it unnecessary to illustrate the same.

I have explicitly described the preferred embodiment of my invention in order to 29 impart an exact understanding of the said embodiment in all of its details. I do not desire, however, to be understood as limiting myself to the precise construction and configuration disclosed, my invention being defined by my appended claims within the 33 scope of which modifications may be made without departure from my invention.

Having thus described the invention, what I claim as new is:—

- 30 1. In combination, an upright pipe having a lateral arm terminating in an upright portion, and a bowl having a concave bottom, and a central rounded protuberance in which is a vertical bore receiving the 35 upright terminal portion of the pipe arm, and also having a series of discharge apertures about and adjacent to the base of said rounded protuberance, and further having a rim with an annular bore in communication 40 with the upper end of said upright pipe and jet apertures in communication with said bore and directed toward the concave bottom and the base of the said protuberance.
- 45 2. In combination, an upright pipe having a lateral arm terminating in an upright portion, and a bowl having a concave bottom, and a central rounded protuberance in which is a vertical bore receiving the upright 50 terminal portion of the pipe arm, and also having a series of discharge apertures about and adjacent to the base of said rounded protuberance, and further having a rim with an annular bore in communication with the 55 upper end of said upright pipe and jet apertures in communication with said bore and directed toward the concave bottom and

the base of the said protuberance; the said bowl being equipped with a pendent waste conduit in coincidence with the said series of discharge apertures and being further provided in its bottom adjacent to said rim with overflow apertures spaced apart, and conduits arranged under the bottom and extending between said overflow apertures 60 and the said pendent waste conduit at points adjacent to the lower ends of the said discharge apertures.

3. A cuspidor bowl having a concave bottom, and a rounded central protuberance thereon and means in said protuberance for conducting flush water to the top of the center of the protuberance and further having a pendent waste conduit, and discharge apertures through the bottom and arranged 70 about and adjacent to the base of the said protuberance.

4. A cuspidor bowl having a concave bottom, and a rounded central protuberance thereon and means in said protuberance for conducting flush water to the top of the center of the protuberance and further having a pendent waste conduit, and discharge apertures through the bottom and arranged 75 about and adjacent to the base of the said protuberance; said bowl also having a rim with a bore adapted to be connected to a source of water supply and with jet apertures in communication with said bore and directed toward the upper surface of the 80 bottom and said protuberance, and a shoulder between the said jet apertures and the inner side of the rim, and overflow apertures adjacent to the rim and conduits under the bottom and between said overflow apertures and the pendent waste conduit at points 85 adjacent the lower ends of the first named discharge apertures.

5. A cuspidor bowl having a concave bottom, and a central rounded protuberance thereon and a bore through the center of said protuberance to a point at the top thereof and also having a pendent waste conduit, apertures about and adjacent to the base of the protuberance and connecting the upper side of the bottom with said waste conduit, a rim with a bore and jet apertures, overflow apertures through the bottom adjacent to said rim, and conduits between the overflow apertures and the pendent 100 waste conduit.

In testimony whereof I affix my signature.

WILLIAM HENRY HAZLITT.
